United States Patent Office.

JOHN R. MARTIN, OF BOOTHBAY, MAINE, ASSIGNOR TO SAMUEL K. HILTON OF PORTLAND, MAINE.

Letters Patent No. 61,625, dated January 29, 1867.

IMPROVEMENT IN FISHING LINE SINKERS.

The Schedule referred to in these Letters Patent and making part of the same:

TO ALL WHOM IT MAY CONCERN:

Be it known that I, JOHN R. MARTIN, of Boothbay, in the county of Lincoln, and State of Maine, have invented a new and improved Fish Sinker or Fishing Lead; and I do hereby declare that the following is a full and exact description thereof, reference being had to the accompanying drawings, and to the letters of reference marked thereon.

Figure 1 is a perspective view; and

Figure 2, a side elevation and section.

A is a nut or burr, working upon two disconnected parts of the staple B, as shown in Figure 2. C is a chamber or cavity in the body of the lead J J. D is a door, working upon the hinge O, and fastened, when closed, by the screw K. E is a hawse, bar, or arm of copper, composition, or other metal, connecting with the body by a screw at M. F and G are weights of lead, or other heavy substance, made of proper size and form to fit the chamber C. H H is a plate of copper, composition, or other metal. L and M are swivels, which may be dispensed with if preferred. The body, J J, of lead or other metallic substance, is run or moulded in any desired size or form upon the plate H H of copper, composition, or other metal, of properly corresponding size and form, and firmly held thereto by the shoulders N N, by the staple B, of copper or other metal, (which is itself cast in the body and additionally secured by the screw P,) by the screw of the arm E at M, which passes in through the plate into the body, and by small screws inserted *ad libitum*. The nut A is sufficiently large to prevent the swivel L from falling down.

The general shape of the sinker here adopted by me is old, but the arrangements above named and described are all new, to the best of my knowledge and belief. The advantages of this sinker over all others will be apparent. It may be rendered of greater or less weight by means of the loose weights fitting the chamber, and so used for different depths of water. It may be readily detached from the line, and the disentangling of fishermen's lines will be thus greatly facilitated. The "hawse" is readily detached, and the sinker is then much more conveniently used for a sounding-lead.

I claim as my invention—

1. The connection of a plate of copper, or other hard metallic substance, with a body of lead, or other soft metallic substance, and the arrangement of a chamber therein enclosing weights of lead or other heavy substance, either or all of which may be removed or replaced at pleasure.
2. The fixing firmly in the upper part of the body of a staple of copper, or other metallic substance, with disconnected parts, (affording sufficient space for the admission of a swivel or line,) and a nut or burr working upon both parts of the staple at the same time, or one part alone, so that the sinker may be detached from the line and replaced at pleasure.

JOHN R. MARTIN.
